UNITED STATES PATENT OFFICE.

WILLIAM J. O'LEARY, OF MONTREAL, QUEBEC, CANADA.

DESIGN FOR A CASING FOR ELECTRIC FAN AND MOTOR OR SIMILAR ARTICLES.

51,098.

Specification for Design.

Patented July 31, 1917.

Application filed June 12, 1917. Serial No. 174,363. Term of patent 14 years.

To all whom it may concern:

Be it known that I, WILLIAM J. O'LEARY, a subject of the King of Great Britain, residing at Montreal, in the Province of Quebec, Dominion of Canada, have invented a new, original, and ornamental Design for a Casing for Electric Fan and Motor or Similar Articles, of which the following is a specification, reference being had to the accompanying drawing, forming a part thereof.

Figure 1 is a front elevation of a casing showing my new design; and
Fig. 2 is a side view thereof.

I claim:

The ornamental design for a casing for electric fan and motor or similar articles, substantially as shown.

Signed by me at Montreal, Province of Quebec, Dominion of Canada, this 7th day of June, 1917.

WILLIAM J. O'LEARY.
